185,193

COMBINED DISPLAY, FOOD WARMER, AND SELF-SERVICE STAND

Philip A. Dill, Dallas, Tex.

Application January 9, 1958, Serial No. 49,182

Term of patent 14 years

(Cl. D81—10)

Figure 1 is a top plan view of the combined display, food warmer and self-service stand;

Figure 2 is an end elevation of the same;

Figure 3 is a front elevation of the stand; and

Figure 4 is a rear elevation of the stand.

I claim:

The ornamental design for a combined display, food warmer and self-service stand, substantially as shown.
